US00D785154S

(12) **United States Design Patent** (10) Patent No.: **US D785,154 S**
(45) Date of Patent: **** Apr. 25, 2017**

(54) **AIR FILTRATION DEVICE**

(71) Applicant: **Illinois Tool Works Inc.**, Glenview, IL (US)
(72) Inventors: **Stephen J. McPhiliamy**, Chicago, IL (US); **Antonio J. Belton**, Richton Park, IL (US); **John S. White, Jr.**, Chicago, IL (US); **Ryan L. Francis**, Palatine, IL (US)

(73) Assignee: **Illinois Tool Works Inc.**, Glenview, IL (US)

(**) Term: **15 Years**

(21) Appl. No.: **29/562,141**

(22) Filed: **Apr. 22, 2016**
